UNITED STATES PATENT OFFICE.

ROBERT E. CAMPBELL, OF SAN FRANCISCO, CALIFORNIA.

MATTRESS-FRAME.

SPECIFICATION forming part of Reissued Letters Patent No. 9,564, dated February 15, 1881.

Original No. 232,334, dated September 21, 1880. Application for reissue filed October 18, 1880.

To all whom it may concern:

Be it known that I, ROBERT E. CAMPBELL, of San Francisco, in the county of San Francisco and State of California, have invented 5 new and useful Improvements in Mattress-Frames, of which the following is a specification, reference being had to the accompanying drawings, in which—

Figure 1 is a perspective representation of 10 my improved mattress-frame attached to the posts of a bedstead; Fig. 2, a vertical section of the ratchet, taken longitudinally with the side rails of the mattress-frame; Fig. 3, a section of the ratchet and ratchet-stand, taken 15 on line $x x$, Fig. 2; Fig. 4, a perspective representation of the pawl removed from the other parts; Fig. 5, a top view of the ratchet-stand.

The object of the present invention is to improve 20 the bed-bottom patented to David W. Taylor on August 29, 1876, No. 181,605.

The nature of invention consists in the novel construction of the ratchet, ratchet-stand, and pawl, as combined with the swell-roller, 25 to hold the latter in a fixed position after it has been turned to tighten the fabric which supports the bedding, and in cross-bars placed in the side rails below the rollers, to hold the roller-journals in position in their respective 30 stands, in combination with single bolts at the corners of the mattress-frame to hold the parts together, as specified.

A A represent the side rails to the mattress-frame, and E E are the end bars. F is the 35 same form of swell tension-rollers shown in said Letters Patent. G G represent what I term "ratchet-stands," which are in bracket form, and are formed on their concave edges with recesses K, to permit a free movement of 40 the ratchets H. The margins of these recesses are inclined inward to form bearings to fit conical journals L on both sides of the ratchets H H. The function of bearings S S is to sustain the strain put on the roller F in stretching 45 the fabric, and the object of beveling them inward is, that the conical bearings L L on the ratchet H may prevent such a longitudinal movement of the roller as would cause the ratchet to grind against the ratchet-stand. 50 The inside prongs of the stand are formed on a line with the roller, that the wire fabric may extend to the ratchets H H.

A pawl, I, is fitted into a recess formed in the lower part of each stand G, and held in place by pivots e e. The end n of the pawl is 55 fitted to engage the ratchet H, and the end m is weighted, so as to cause the end n to catch onto the ratchet when the roller is turned in the direction indicated by dart 3, and also to permit a free movement of the roller in the 60 direction of dart 2.

The stands G, rails A, and cross-bars E are held together by bolts J, Fig. 2. Said bolts also pass through the shanks P P of the thimble-sockets D D and firmly unite the parts at 65 each corner by a single bolt.

The advantage of this construction is the combination of the fewest possible pieces, a saving of material, and attaining strength by lessening the number of holes to receive fastenings. Further than this, provision is made 70 for readily "taking down" the mattress-frame for shipment in compact form.

The cross-bars E extend into the side rails, A A, below the roller F, in a mattress-frame, 75 in order to prevent the rails A from twisting, and thereby injuriously affecting the journals of the rollers F in their respective stands, and also strengthening the angles of the frame.

The thimble-sockets pass onto the posts C 80 C and unite the mattress-frame with the other parts to form a complete bedstead; but this feature is not claimed in this application.

I claim and desire to secure by Letters Patent— 85

1. The ratchet-stand G G, recessed at K, and formed with beveled bearings S S, in combination with the ratchets H H, the conical journals L, located at the sides of the ratchet, and the weighted pawls I I, placed in recesses 90 below the ratchets H H, the bolts J J, side rails, A A, and roller F, as and for the purpose specified.

2. The ratchet-stands G, side rails, A A, cross-bars E, and thimble-shanks P, in combination with the single bolts J, passing through them at each corner at the head of the mattress, and connecting them, as specified. 95

ROBERT E. CAMPBELL.
